CONVEYER

Arnold Redler, Stroud, England, assignor to
 Redler Conveyor Company, Quincy, Mass., a
 corporation of Massachusetts

Application August 7, 1936, Serial No. 94,785
 In Great Britain August 16, 1935

3 Claims. (Cl. 198—168)

This invention relates to endless conveyers, and more particularly to conveyers of the open flight type. It seeks to provide a construction of conveyor which may enable economies to be effected in first cost, and also to provide for some degree of simplification, particularly in regard to power transmission means, means for maintaining correct tension of a conveying element, and in other respects. The invention also seeks to provide a cheap form of chain which will fulfill certain requirements and, in particular, may enable an en masse conveyer element to be run over a relatively small sprocket whereby certain problems in relation to speed reduction in transmission systems may be met.

According to one feature of this invention, the driving sprocket in an open flight conveyer of the endless chain type is made substantially less in pitch diameter than the spacing between the two runs of the chain, and a type of chain is preferably adopted which will run satisfactorily over a small sprocket, and also means are preferably provided in the form of what may be termed a shield, which will not only obviate or diminish the risk of the load immersing or jamming the sprocket as the chain passes around it, but also enable the chain to be run with varying degrees of slack in its idle or return travel, so that tensioners or other adjusting means may be dispensed with. The type of chain adopted may also, whilst affording full articulation which is desirable for the passage over the small sprocket, minimize the risk of jamming even though its links be packed with the conveyed material.

The invention is illustrated in the accompanying drawing diagrammatically; Fig. 1 shows a side elevation of one end of a conveyer; Fig. 2 is an enlarged side view of a terminal sprocket and chain passing therethrough; Fig. 3 is a plan view of the device of Fig. 2; Fig. 4 is a view, similar to Fig. 2, of an alternative form of chain and sprocket; and Fig. 5 is a plan corresponding to Fig. 4.

In Fig. 1 the open flight conveyer comprises a trough with a floor 1 and vertical parallel walls 2, the floor having an outlet 3. A chain, diagrammatically indicated at 4, runs in the direction of the arrows 4A along the floor 1 of the trough. The material 5 is carried along within the trough by the co-acting links of the chain in the fashion of open flight conveyers, and the trough is, in accordance with this type of conveyer, of considerable height in relation to the depth of the chain itself. This can be perceived from Fig. 1, in which the material 5 is seen to be heaped on

the chain 4. The chain 4 runs beneath a terminal sprocket 6 situated within the trough, the end wall 1 of which may be conveniently curved as at 7A more or less concentrically with the sprocket 6, but leaving a clearance for the passage of the chain 4 and perhaps some material. The chain runs around the terminal sprocket 6, which is power driven by any suitable external source connected to its shaft 6A, and returns over the top of the sprocket more or less in the path shown in Fig. 1, and with a definite slack loop at 4B which is supported by the upper surface of a baffle 8 which comprises a sort of false floor extending across the trough from side to side and runs horizontally throughout the greater part of the length of the trough, but towards the end 7 inclines downwardly until its extremity near the sprocket 6, where it is again curved upwardly more or less to follow the sag of the chain at 4B. In the inclined part an opening 8A is formed, through which material may pass, and the fact that the baffle 8 inclines down to a fairly close proximity to the floor 1 means that if more than a certain amount of material is being conveyed in the direction of the arrows 4A and towards the sprocket 6, the material will build up in a heap, as illustrated at 9, and will consequently prevent the material on top of the baffle 8 from falling through the opening 8A, so that material will be conveyed up the slope of the baffle 8 as indicated at 10. This material on top of the baffle 8 may again fall down through the opening therein at 8B, which also may be an ordinary loading opening for the conveyer, so that it rejoins the mass 5 and is again available for delivery through the chute 3. In this way jamming and overloading is prevented; if, for example, there is some temporary obstruction to the outlet of 3, then a part of the load is carried on towards the terminal 6, and although perhaps mere small and incidental quantities of load simply get carried around the sprocket and fall back again through 8A, there will come a time when this is sufficiently built up for the load at 10 to form, and consequently for return to 5 to be effected. This arrangement not only automatically effects some degree of evening out of delivery, but it provides a capacity for dealing with temporary overloads or choking of outlet. The particular form of sprocket and chain which will be described in greater detail hereafter, facilitates this in that it enables a small sprocket to be used which will consequently deal with loads as above described without jamming. Again, the small sprocket is well adapted to operate with a chain with a high

degree of articulation, i. e. with very short links.

One form of chain and sprockets is illustrated in Figs. 2 and 3. In this case the sprocket 6 on its shaft 6A has three pairs of radially projecting bosses such as 11, but otherwise presents a plain cylindrical surface. The chain is composite and comprises a pair of ordinary roller chains built up of overlapping links, pivots, and rollers which act as spacers upon the pivots. The two chains so formed are shown at 12 and 13, and they are interconnected at intervals by flights in the form of metal strips 14 presenting flat surfaces in the direction of motion and having their ends bent at right angles to form plates as at 15 which are attached to the chains 12 and 13 by being carried on an adjacent pair of pivots, as can be seen more clearly in Fig. 3. The flights 14 span the trough almost completely, and the chains 12 and 13 simply roll around the cylindrical part of the sprocket 6, whilst the bosses 11 are so spaced peripherally as to engage adjacent flights 14 in sequence, thus driving the conveyer element as required.

A variation is shown in Figs. 4 and 5, in which a single roller chain is employed; there is again a sprocket 6 of plain cylindrical form, but in this case half-way between its ends it has radially projecting sprocket teeth 16 which may conveniently be an actual wheel like a bicycle sprocket, embodied in the sprocket 6. The teeth 16 are engaged by a single roller chain 17 which has laterally projecting flights 18 formed of strip metal or the like, with ends bent at 18A for attachment to the chain 17, as can be seen in Fig. 5. In this case, of course, the drive from the sprocket to the chain is through the rollers of the chain, and not through the flights, and the flights are supported during their passage around the terminal by the cylindrical part of the sprocket 6. In each case it will be seen that the chain is of a high degree of articulation and can therefore pass readily around a relatively small sprocket, and yet the spacing of adjacent flights is consistent with en masse conveying. It follows that a sprocket may be used which is of appreciably less depth than the conveyer trough, or the conveyed load. The terminal at the other end of the conveyer, which is not shown in the drawing, may simply be a plain cylindrical roller without any chain-engaging means. Owing to the relative smallness of the driving sprocket of the conveyer, it may be found possible to drive from ordinary sources of power without reduction gearing; for example, the spindle 6A may merely have a pulley perhaps considerably larger than the sprocket itself, and thus economy in cost and weight may be achieved.

Having now particularly described and ascertained the nature of my said invention, and in what manner the same is to be performed, I declare that what I claim is:

1. In a conveyer of the character described,

in combination, a casing provided with a discharge outlet, an endless open flight conveyer member traversable through the casing, a driving sprocket around which the conveyer member passes to constitute the lower run of the conveyer the working run, said discharge outlet being disposed at a substantial distance in advance of the driving sprocket, a supporting plate having one end disposed adjacent the sprocket and onto which material passing over the sprocket is delivered, said plate constituting a support for the upper run of the conveyer member, said plate being provided with an opening through which material being conveyed by the lower run of the conveyer may pass prior to reaching the driving sprocket when the outlet from the conveyer casing becomes choked to thereby be conveyed by the upper run of the conveyer member over said supporting plate.

2. In a conveyer of the character described, in combination, a conveyer casing provided with a discharge outlet, an endless open flight conveyer member traversable through the casing, a driving sprocket over which said conveyer member is arranged to pass to constitute the lower run of the conveyer member the working run, the portion of the upper run of the conveyer member adjacent the driving sprocket being disposed a short distance above the lower working run of the conveyer member, said discharge outlet being disposed at a substantial distance in advance of the driving sprocket, a supporting plate for the upper run of the conveyer member having one end disposed adjacent the driving sprocket and provided with an opening through which material piling up in advance of the driving sprocket when the outlet becomes jammed may pass to be conveyed by the upper run of the conveyer member over the remainder of said supporting plate.

3. In a conveyer of the character described, in combination, a conveyer casing provided with an outlet in the bottom thereof, a conveyer member of skeleton type arranged to be drawn through the casing, a terminal sprocket over which the conveyer member passes, said outlet being disposed at a substantial distance in advance of the driving sprocket, the lower run of the conveyer member constituting the working run and a supporting plate for the upper run of the conveyer having an opening disposed adjacent the terminal sprocket and a second opening at a distance therefrom whereby to permit material piling up in advance of the terminal sprocket when the outlet of the conveyer casing is closed to by-pass onto said plate to be conveyed by the upper run of the conveyer member and discharged through said second opening to be thereby returned again to the material being conveyed by the lower run.

ARNOLD REDLER.
